UNITED STATES PATENT OFFICE.

ISAAC R. STOUT, OF WALLA WALLA, WASHINGTON.

PUMP.

950,968.

Specification of Letters Patent.

Patented Mar. 1, 1910.

Application filed April 10, 1909. Serial No. 489,042.

To all whom it may concern:

Be it known that I, ISAAC R. STOUT, citizen of the United States, residing at Walla Walla, in the county of Walla Walla and 5 State of Washington, have invented certain new and useful Improvements in Pumps, of which the following is a specification.

My invention relates to pumps or other water raising devices, and more particularly 10 to such devices operated by compressed air, and the object thereof is to provide submerged barrels together with automatic valves to alternately empty the same as they become filled and produce a steady constant 15 stream.

Further objects and the advantages of my invention will be apparent to those skilled in the art from the following description in which reference is made to the accompanying 20 drawing, forming a part of this specification, and in which,

Figure 1 is an elevation of my improved device. Fig. 2 is an enlarged sectional view through the upper valve portion of my device. Fig. 3 is a similar view through one 25 of the pump barrels and its valve. Fig. 4 is an enlarged detail sectional view of the pump barrel valve shown in Fig. 3, and, Fig. 5 is a similar view of my preferred 30 connection between the casings forming the chambers of the inlet and outlet air valves and the piston and connecting chambers.

In the practical embodiment of my invention, I provide a pair of pump barrels 35 1 and 2, both of which are to be submerged well below the water line, as shown in Fig. 1, and provided in their bases with inwardly opening intake valves 3, (Fig. 3), surrounded by a mesh or perforated metal 40 straining cylinder 4. A pipe 5 leading upwardly alongside the superposed vertical aligned barrels 1 and 2, is connected to the lower ends thereof by fittings 6, in which are located outwardly opening valves 7, said 45 pipe being extended to the surface and constituting the water outlet pipe.

Mounted upon the upper end of each of the pump barrels 1 and 2 are pump valves 8, one of which is illustrated in Fig. 4. Each 50 of these pump valves comprises a tubular casing 9, which, by its contracted lower stand portion 10, also tubular, communicates within the pump barrel upon which it is secured, through an opening in the upper end of the latter. The upper end of the stand portion 10 forms a valve seat 11, at

the base of a short cylinder 11^a, for a downwardly closing valve 12, connected by means of a valve rod 13, to a float 14, arranged within its pump barrel a short distance 60 above the level of its outlet fitting 6, and within a hood 15, opening downwardly and secured to the barrel wall, and through which said valve rod extends. The stand portion 10, also supports a hood 16, within 65 casing 9, and upon legs 17 which guide valve 12 in its movements. The upper end of hood 16 forms a valve seat for a needle valve 18, and communicates with a pipe 19, extending upwardly within a pipe 20, from the upper 70 end of casing 9. The hood 16 is also provided with an opening 21 through its wall just below the seat of valve 18, and casing 9 may also be provided with a pipe 22, leading from the upper portion downwardly 75 through the upper portion of the pump barrel. The needle valve 18 is provided with a plate 23, supported therefrom, and spaced therebelow, by rods 24, said plate 23 having a central aperture through which 80 the upwardly projecting end 25 of valve rod 13 above the valve 12, extends, said projecting end 25 having a nut 26 thereon above said plate 23. Thus, as shown, when the conical valve is in the open position (Fig. 85 4), raised thereto by float 14, it is within the lower end of hood 16, and protected from the action of the air which flows downwardly through casing 9, from air pipe 20, into the pump barrel through the tubular 90 stand 10. Also as shown, in this position, the upper end 25 of valve rod 13, presses the needle valve 18 firmly into its seat in the lower end of pipe 19, closing port or opening 21. It will be seen that when the water 95 level in the pump barrel falls, the float 14 descends, pulling down valve 12 into the path of the air which firmly closes the same in cylinder 11^a and upon seat 11, and that the nut 26 upon the valve rod end 25, strikes 100 the plate 23 in its downward movement and pulls the needle valve 18 slightly from its seat, sufficient to uncover port or opening 21, whereby the air in pipe 20 and casing 9 is let into pipe 19 and also the air in the pump 105 barrel through pipe 22 having therein a valve 27 opening upwardly toward casings 9.

The upper ends of the outer air pipes 20 and 28 of the pump barrels 1 and 2 respectively, lead from the upper and lower chambers 29 and 29^a respectively of the inlet air valve 30, the central chamber 31 of which is

separated from said upper and lower chambers 29 and 29^a, by centrally apertured disks 32 and 33 respectively, forming valve seats as hereinafter described.

5 Pipes 20 and 28 are connected by branch pipes 34 and 35 respectively to the upper and lower chambers 36 and 37 of the outlet air valve 40, the central chamber 38 of which, as in the case of the inlet air valve, is separated from said upper and lower chambers 36 and 37, by centrally apertured disks 39 and 39^a, forming valve seats.

10 Inlet and outlet air pipes 41 and 42 lead to and from the central chambers 31 and 38 15 of air valves 30 and 40 respectively.

15 The inlet and outlet air valves 30 and 40, which are superposed and vertically aligned as shown, are connected, by a tubular casing 43 extending between their lower and upper 20 chambers 29^a and 36 respectively. Said valves 30 and 40 also have tubular casings 44 and 45 extending upwardly and downwardly therefrom respectively, and connecting their upper and lower chambers 29 and 25 37 respectively with piston chambers 46 and 47. The valves 30 and 40, tubular casings 43, 44 and 45, and piston casings 46 and 47 are thus longitudinally in a series, and have extending therethrough a valve rod 48.

30 Within valve 30 rod 48 is provided with a valve 49 in chamber 31 between disks 32 and 33 and capable of seating in the apertures of each of said disks. Within valve 40 rod 48 is provided with valves 50 and 51 respectively located in chambers 36 and 37 and adapted to seat in the apertures of disks 39 and 39^a, one at a time. Thus as shown in Fig. 2, when valve 49 is seated in disk 32, valve 51, is seated in disk 39^a, while upon 40 longitudinal movement of rod 48 to seat valve 49 in disk 33, valve 51 will be moved away from disk 39^a and valve 50 seated in disk 39. The means for moving rod 48 longitudinally comprise piston heads 52 and 53 45 mounted upon the ends thereof in piston chambers 46 and 47, which chambers 46 and 47 have air pipes 54 and 55 and pipes 56 and 57 leading to the upper and lower portions thereof respectively.

50 As shown in Fig. 2, valve rod 48 is in two longitudinal sections, the lower end of the upper section being provided with a depending sleeve 48^a, screwed thereon, and having an aperture in its lower end through which 55 the upper end of the lower section projects and is provided within said sleeve with a head 48^b. Thus the several valves may seat uniformly and evenly.

55 The upper pipes 54 and 56 of chambers 46 and 47 respectively, are connected by vertical and horizontal pipes 58 and 59, the latter of which has a minute aperture 60, to the upper end of the inner air pipe 61 of the lower pump barrel valve 8, which extends 65 upwardly within the air supply pipe 28

thereof, while the lower pipes 55 and 57 of chambers 46 and 47 are connected by vertical and horizontal pipes 62 and 63, the latter of which has a minute aperture 64, to the inner air pipe 19 of the upper pump barrel valve 8 which extends upwardly within the air supply pipe 20 thereof. Thus, referring now to Figs. 2 and 3, it will be seen that the parts are in position corresponding to the exhausting of the water from the lower 70 pump barrel 2, air being admitted from air inlet pipe 41 through disk 33 of the inlet valve 30, and through the lower pump barrel supply pipe 28, and air being exhausted from the supply pipe 20 of the upper pump 75 barrel, through disk 39 of the outlet air valve and through the outlet air pipe 42. As soon as the water level in the lower pump barrel falls to an extent permitting the float 80 therein to descend, its air supply valve will be closed, opening the needle valve of its inner air pipe 61, and permitting air to enter therein and pass therethrough and through branch pipes 59, 58, 56 and 54 to the piston chambers 46 and 47 above the 85 pistons 52 and 53 therein. These pistons 52 and 53 being of larger area than the valves 49, 50 and 51, the air thrown thereagainst will cause downward longitudinal movement of valve rod 48, seating valve 49 in 90 disk 33, and valve 50 in disk 39, and unseating valve 51, thus deflecting the inlet air through disk 32 into the upper end of the upper pump barrel supply pipe 20, and opening communication between the lower pump 95 barrel supply pipe 28, by its branch 35, through disk 39^a, to the outlet air pipe 42. The minute apertures 60 and 64 in pipes 59 and 63 gradually relieve the pressure in their respective piston operating pipes, the valve 100 rod 48 being held balanced in either of its positions, to which it is moved, by the inlet and outlet air between the valves 49, 50 and 51 and pistons 65, 66 and 67 secured upon said rod 48 within the casings 43, 44 and 45 105 respectively, which pistons 65, 66 and 67 are, as shown, of less area than the valves 49, 50 and 51.

110 While in Fig. 2, I have shown a conventional form of connection between the casings forming the several valve chambers, my preferred connection is shown in Fig. 5, in which the casing 68 corresponds to the casing forming chamber 31 in Fig. 2, and casing 69 corresponds to the casing forming chamber 29 in said figure. Casing 68 is provided just below its end with an internal circular flange 70, which supports the apertured disk 71, corresponding to disk 32 in Fig. 2, and is externally threaded. Casing 115 69 which is of smaller diameter than casing 68, is provided with an internal circular flange 72, resting upon disk 71, and is externally threaded for the reception of a metallic packing ring 73 screwed down tight 120

against the end of casing 68. A coupling sleeve 74, having one inwardly curved circular edge 75 and internally threaded, is screwed upon the external threads of the 5 casing 68, and engages with its said curved edge, the packing ring 73, to hold the casings together in air-tight relation.

Having fully described my invention, I claim:

10 1. A pump of the character described, comprising submerged pump barrels, valves arranged upon each of said barrels and adapted to open in opposite directions to each other, means for directing air pressure 15 into said barrels, one of said valves being adapted to regulate the inlet of air pressure into said barrels, the other of said valves being adapted to actuate said air pressure directing means, and common means for actuating both of said valves when the water 20 level in said barrels is varied, substantially as described.

2. A pump of the character described, comprising submerged pump barrels, a valve 25 arranged upon each of said barrels and adapted to open upwardly to admit of air pressure into said barrel, means for directing air pressure into said barrel, a downwardly opening valve arranged upon said 30 barrel for operating said pressure directing means, and a float arranged within said barrel and connected to said upwardly and downwardly opening valves for alternately opening and closing the same, substantially 35 as described.

3. A pump of the character described, comprising submerged pump barrels, an air pressure directing mechanism, air pressure pipes communicating with said submerged barrels and said air pressure directing mechanism, each of said submerged valves being provided with an upwardly opening valve, for admitting air pressure from said air pressure directing mechanism, 40 each of said submerged barrels being further provided with a downwardly opening valve,

a pipe communicating with said downwardly opening valve and said air pressure directing mechanism and adapted to admit air therethrough for operating the same, a 50 float mechanism arranged within said barrel and connected to said upwardly and downwardly opening valves and adapted to alternately open and close the same, substantially as described.

55 4. A pump of the character described, comprising submerged pump barrels, an air pressure directing mechanism, pipes communicating with said submerged barrels and said air pressure directing mechanism, each 60 of said submerged pump barrels being provided with an upwardly opening valve for admitting air pressure from said air pressure directing mechanism, each of said submerged barrels being further provided with 65 a downwardly opening valve, a pipe communicating with said downwardly opening valve and said pressure directing mechanism for admitting air through the same for operating the said air pressure directing 70 mechanism, common means for alternately opening and closing said upwardly and downwardly opening valves when the water level in said barrel is varied, said air pressure directing mechanism comprising an air 75 pressure supply and exhaust valves, said air pressure supply valve being adapted to have alternate air pressure communication with said submerged pump barrels, said exhaust valve being adapted to have alternate air 80 exhaust communication with said submerged pump barrels, common means for operating said air pressure supply and exhaust valves comprising a reciprocating rod and pistons arranged thereon, substantially 85 as described.

In testimony whereof I affix my signature in presence of two witnesses.

ISAAC R. STOUT.
